United States Patent Office

Des. 197,454
Patented Feb. 4, 1964

197,454

LAWN SPRINKLER

Graham Fee and William E. Portz, Geneva, Ohio,
assignors to True Temper Corporation, Cleveland, Ohio,
a corporation of Ohio

Filed Nov. 6, 1962, Ser. No. 72,396

Term of patent 14 years

(Cl. D91—1)

FIG. 1 is a side elevational view of a lawn sprinkler, showing our new design;

FIG. 2 is an end elevational view thereof;

FIG. 3 is a top perspective view thereof.

The dominant features of our design reside in the portion shown in solid lines.

We claim:

The ornamental design for a lawn sprinkler, as shown and described.
